BLADE HOLDER

James Benda, Wausau, Wis.

Application April 21, 1938, Serial No. 203,385

5 Claims. (Cl. 51—222)

This invention relates to a sickle blade holding apparatus for whetstone grinders.

It is an aim of this invention to provide a device adapted to be supported by a whetstone support and having means to removably support a blade to be sharpened.

More particularly, it is an object of this invention to provide a device comprising a relatively few parts which are pivotally, swivelly and slidably connected so that the blade supported thereby to be sharpened may be moved into or out of engagement with a grinding wheel and adjusted laterally thereto for sharpening various portions of the blade.

It is a further object of this invention to provide a device which may be economically constructed, to be very durable, and which may be readily attached to or removed from a grinding bench. An important advantage of this invention resides in the fact that the blade will be positively supported and may readily be held rigid by the operator in proper position to sharpen the blade with a proper bevel, the device being so constructed, that it will properly adjust the blade to the grinding wheel when in engagement therewith.

Other objects and advantages of the invention will hereinafter become more fully apparent from the following description of the drawings which illustrate a preferred form of the invention, and wherein:

Figure 1 is a side elevational view showing the device attached to a whetstone bench and supporting a blade in engagement with the stone for sharpening.

Figure 2 is a top plan view of the invention.

Figure 3 is a rear elevational view of the same.

Figure 4 is a vertical sectional view taken on the line 4—4 of Figure 3.

Figure 5 is a fragmentary side elevational view showing one of the clamping members held in an upright position to receive a blade to be sharpened.

Figure 6 is a horizontal sectional view taken on the line 6—6 of Figure 5.

Figure 7 is a vertical sectional view taken on the line 7—7 of Figure 6, and

Figure 8 is a sectional view taken on the line 8—8 of Figure 1 showing the cross-sectional shape of the periphery of the grinding wheel.

Referring more particularly to the drawings wherein like reference characters designate like or corresponding parts, 10 designates generally a whetstone wheel and 11 its support or bench, 55 these parts being of conventional form and shown

merely to illustrate the application of the invention which will hereinafter be described.

The blade holder designated generally 12 and comprising this invention includes a pair of angle members 13 adapted to be connected by the nut and bolt fastenings 14. Members 13 are adapted to be clamped to the bench or support 11 as seen in Figures 1, 3 and 4. Bearings 15 are secured at either end and on the upper side of the upper member 13 to journal the opposite ends of a shaft 16.

An arch 17 formed of angle-shaped telescopic sections 18 and 19, has a pair of apertured ears projecting from its depending ends 19 through which extends the shaft 16 and by which arch 17 is pivotally mounted. Parts 18 and 19 are provided with a plurality of equally spaced apertures 21 adapted to be aligned to receive the nut and bolt fastenings 22 to rigidly retain the arch 17 in an extended or retracted position as desired 20 depending upon the diameter of the wheel 10, as will hereinafter become more clearly apparent.

A sleeve 23 is suitably secured in a vertical position intermediate of the upper end of the arch 17.

A crosshead, designated generally 24 and comprising a head 25 and a depending reduce shank 26 which is swivelly mounted in sleeve 23 and held in position therein by nut 27 which engages its threaded end 28. Head 25 is provided with a longitudinal bore 29, and with slots 30 at opposite ends thereof disposed in a horizontal plane and communicating with the bore 29 as best seen in Figure 3.

Connected to the opposite ends 32 of frame 31, 35 are the clamping members designated generally 33. Clamping members 33, as best seen in Figures 4 and 5, comprise the jaws 34 which are rigidly secured to ends 32, and the jaws 35 which are slidably mounted on the bolts 30 which extend 40 through corresponding openings 37 in jaws 34 and 35. Nuts 38 engage the threaded ends of bolt 36 to retain the jaws 35 in position thereon, and the bolts 36 are provided with expansion coil springs 39 which normally urge the jaws 34 and 35 away from each other.

40 designates generally a sickle blade, shown to illustrate the application of the invention, comprising a plurality of teeth 41 connected by bar 42 extending along one side thereof.

From the foregoing it will be seen, that when the arch 17 is in a position as seen in Figure 4, the frame 31 may be turned in bore 29 until its ends 32 are perpendicular with head 25, when by moving the frame lengthwise of the head 25 55

one of the ends 32 will engage the notch 30 to retain clamping members 33 in an upright position, as seen in Figure 5, to permit the bar 42 to be positioned between the jaws 34 and 35 and clamped therein by tightening nut 38. Bar 42 is clamped between jaws 34 and 35 as best seen in Figure 4, so that the teeth 41 project outwardly from the clamping member 33. Arch 17 is then swung toward the wheel 10 on its pivot 16, and frame 31 is turned in bore 29 until the teeth 41 and blade 40 contact the periphery of wheel 10. Arch 17 and frame 31 are adjusted until the teeth 41 are at the proper angle to the wheel 10 for sharpening, as best seen in Figure 1. The periphery 43 of wheel 10 as seen in Figure 8 is beveled to a point to engage adjacent edges of two of the teeth 41 simultaneously, and frame 31 is sidely mounted in bore 29 so that it may be moved transversely relatively thereto to position teeth 41 relatively to wheel 10 and to move the blade laterally of the wheel after each pair of edges has been sharpened. Frame 31 may be of any desired length so that any number of teeth 41 may be sharpened without removing the blade 40 for the clamps 33 for readjustment therein, and the frame 31 is swivelly mounted by the crosshead 24 for fine angular adjustment of the blade 40 relatively to the periphery 43 of the wheel 10 so that the teeth 41 will be ground to a proper bevel thereby. The arch 17 is formed of telescopic sections 18 and 19 so that it may be raised or lowered to adapt the holder 12 for use with grinding wheels of different diameters.

Clamps 33 may readily be modified to support other forms of blades than the blade 40 as shown, and various other modifications and changes may obviously be resorted to and are contemplated, without departing from the spirit and scope of the invention as hereinafter defined by the appended claims.

I claim as my invention:

1. In a device of the class described, a member adapted to be removably secured to a whetstone support, an arch pivotally supported by said member and extending upwardly therefrom, said arch being formed of extensible sections, a T-shaped member swivelly mounted on said arch and having a bore extending through its head, and a yoke slidably mounted in said bore, clamping means at each end thereof adapted to removably engage the blade to be sharpened, said device being adapted to move the blade into and out of engagement with a grinding wheel and for transverse movement of the blade relatively to the grinding wheel.

2. In a holder for blades while sharpening, an arch member pivotally mounted and vertically adjustable, a crosshead swivelly mounted at the upper part of said arch and having a horizontally disposed bore, a U-shaped member having an intermediate portion extending through said bore and pivotally and slidably mounted therein at substantially right angles to the arch member, and clamping means connected to the ends of said U-shaped member and adapted to removably engage a blade to be sharpened, said device being adapted to move a blade into and out of engagement with a grinding wheel and for transverse movement relative to the wheel.

3. In a blade holding attachment for sharpening wheels, clamping means for removably engaging the blade, said clamping means being provided with a U-shaped supporting frame, a crosshead in which said supporting frame is slidably and pivotally mounted, a standard on which said crosshead is swivelly mounted, said frame being slidably and pivotally mounted to move the blade laterally of and toward or away from a grinding wheel, and swivelly mounted by the crosshead for angular adjustment relatively thereto, and said crosshead having means for holding the frame rigidly in a horizontal position away from the grinding wheel for connecting or disconnecting the blade.

4. In a blade holding attachment for sharpening wheels, a pivotally mounted extensible standard, clamping members adapted to releasably engage a blade to be sharpened, said clamping members being mounted on the opposite ends of a U-shaped rod, and means for slidably, pivotally and swivelly mounting said rod relatively to said standard for moving said blade into and out of engagement with a sharpening wheel, laterally thereof and for angularly adjusting the blade relatively thereto.

5. A blade holder comprising an extensible arch shaped member adapted to be pivotally mounted on a whetstone support, a sleeve formed in the top of said arch shaped member and disposed longitudinally thereof, a tube having a laterally projecting shank intermediate of its ends loosely mounted in the sleeve for swivelly mounting the tube relatively to the arch shaped member, a U-shaped rod having its intermediate portion slidably and swivelly mounted in the tube, and clamping elements mounted on the ends of said rod and adapted to be movably mounted thereby laterally of a whetstone, said clamping elements being adapted to detachably support a blade to be sharpened.

JAMES BENDA.
